UNITED STATES PATENT OFFICE.

WILLIAM HENRY LIGHTY, OF MONTICELLO, INDIANA.

BILL AND POSTER HOLDER.

SPECIFICATION forming part of Letters Patent No. 300,274, dated June 10, 1884.

Application filed March 10, 1884. (No model.)

To all whom it may concern:

Be it known that I, WILLIAM H. LIGHTY, a citizen of the United States, residing at Monticello, in the county of White and State of Indiana, have invented a new and useful Bill and Poster Holder, of which the following is a specification, reference being had to the accompanying drawings.

My invention relates to a device for holding bills, posters, dodgers, &c.; and it has for its object to provide a device of this character which shall be cheap and simple in its construction, and one to which the bills may be readily attached or detached from.

15 A further object of the invention is to provide improved means for retaining the clamping-plate in a raised position while the posters or bills are being placed beneath the same.

20 A further object of the invention provides improved means for holding the clamping-plate in contact with the lower strip to which it is attached.

25 With these ends in view the invention consists in the improved construction and combinations of parts hereinafter fully described, and pointed out in the claims.

30 In the drawings, Figure 1 is a perspective view of my invention, showing the same attached to a frame for containing the cards of business-houses, in connection with which it is preferably used. Fig. 2 is a central transverse section. Fig. 3 is a rear view of the clamping-strip and spring-wires, the same being detached from the base-strip.

35 In the accompanying drawings, in which like letters refer to corresponding parts in the several figures, A represents a base-strip, which is provided near its upper edge and near the corners with perforations for the 40 passage of screws or equivalent fastening for securing the base-strip to the wall or other object.

B represents the clamping-strip, which is substantially triangular in cross-section. The 45 front portion of this clamping-strip may be made ornamental by forming it with a molding, as shown in Fig. 1.

At each end of the clamping-strip A are provided downwardly-projecting loops, which

are twisted or bent at their lower ends to form 50 eyes c, the upper ends of said loops being secured in grooves or recesses formed upon the ends of the said strips. These loops are attached to the base-strip by means of wires passing through the eyes thereof, which are 55 attached to the base-plate at one end and secured to the clamping plate or strip A at the other—that is, the wire e, which is attached to the base-strip at one end, is secured to the clamping-strip at the other end of the same, 60 which for convenience we will letter f. The wire g is attached to the end f of the base-strip, and crosses the wire e, and is secured to the end of the clamping-strip. It will thus be seen that a strong and serviceable 65 spring is provided—one that is not liable to get out of order, and one which will securely hold the clamping-strip in close contact with the base-strip.

At about the center of the clamping-strip, 70 and upon the upper edge of the same, is provided an upwardly-projecting pin, i, which is adapted to engage a spring-plate, j, secured upon the upper edge of the base-strip, and provided with a perforation, k, to receive said 75 pin.

Upon the lower front side of the base-strip A are provided pins l, which are adapted to receive the bills or posters, and which register with perforations or recesses formed upon the 80 under side of the clamping-plate, whereby the said posters or bills are securely held upon the same.

It will be seen from the foregoing description that my device is applicable to various 85 uses—as, for instance, it may be used as a clamp for holding curtains, or may be used as a splasher-holder. However, in using the device for holding posters, &c., the same is preferably attached to a frame, as shown in Fig. 1, 90 which contains the business-cards of various establishments.

Having fully described my invention, what I claim as new, and desire to secure by Letters Patent, is—

1. The combination, with a suitable base-strip, of a spring-pressed clamping-plate provided with means of attachment, substantially

as shown, and triangular in cross-section, one of the points of which forms the fulcrum upon which it works, substantially as set forth.

2. The combination, with a suitable base-
5 strip, of a spring-pressed clamping-plate tri-
angular in cross-section, having a pin pro-
jecting upwardly from its upper edge, and a
spring-plate provided with a perforation se-
cured to the base-strip, substantially as set
10 forth.

3. The combination, with a suitable base-
strip, of a spring-pressed clamping-plate, tri-
angular in cross-section, provided with a pin
upon its upper edge adapted to engage a per-
15 foration in a spring-plate secured to the base-
strip, pins projecting outwardly from the lower
end of the base-strip to engage perforations or
recesses formed upon the under side of the
clamping-plate, substantially as set forth.

20 4. The combination, with a suitable base, of
a clamping-strip having depending loops
formed with eyes secured at its ends, wires

secured to the opposite ends of the base-strip
at one end and to the ends of the clamping-
strip at their other ends, substantially as set 25

5. The combination, with a suitable base-
strip, of a clamping-strip having depending
loops formed with eyes secured at its ends,
wires secured to the opposite ends of the base- 30
strip at one end and to the opposite ends of
the clamping-strip at their other ends, said
clamping-plate being provided with a pin
upon its upper edge adapted to engage a per-
foration in a spring-plate secured to the base- 35
strip, substantially as set forth.

In testimony that I claim the foregoing as
my own I have hereto affixed my signature in
presence of two witnesses.

WILLIAM HENRY LIGHTY.
